UNITED STATES PATENT OFFICE.

WILLIAM C. BRAY, OF NEWTON, MASSACHUSETTS, ASSIGNOR TO TUBULAR RIVET & STUD COMPANY, OF BOSTON, MASSACHUSETTS, A CORPORATION OF MASSACHUSETTS.

RIVET AND CAP SETTING MACHINE.

1,161,022.

Specification of Letters Patent. Patented Nov. 23, 1915.

Application filed January 29, 1915. Serial No. 5,121.

To all whom it may concern:

Be it known that I, WILLIAM C. BRAY, a citizen of the United States, residing at Newton, in the county of Middlesex, and 5 State of Massachusetts, have invented certain new and useful Improvements in Rivet and Cap Setting Machines; and I do hereby declare the following to be a full, clear, and exact description of the invention, such as 10 will enable others skilled in the art to which it appertains to make and use the same.

The present invention relates to rivet and cap setting machines and more particularly to the cap feeding mechanism employed in 15 machines of this type.

The object of the present invention is to provide certain improvements in the feeding mechanism causing the caps to be delivered separately and at uniform intervals in 20 operative relation to the setting devices.

With this object in view the several features of the invention consist in certain novel features of construction, combinations, and arrangements of parts hereinafter 25 described and claimed, the advantages of which will be obvious to those skilled in the art from the following description.

In the accompanying drawings illustrating the preferred form of the invention; 30 Figure 1 represents a side elevation of a rivet and cap setting machine embodying the present invention; Fig. 2 is a detail showing a side elevation upon an enlarged scale of a portion of the coöperating cap and rivet feeding chutes and setting mechanism; Fig. 3 is a detail showing a section of the cap feeding chute taken upon the line 3—3 35 of Fig. 2 looking in the direction of the arrow; Fig. 4 is a detail showing a side elevation partly in section of the cap feeding chute and setting anvil with a portion of the rivet setting mechanism in the position which it occupies prior to the setting operation; Fig. 5 is a view similar to Fig. 4 and 40 illustrating the relative position of the parts after the cap has been set upon the rivet; Fig. 6 is a detail illustrating an end elevation of the cap feeding chute with the anvil and supporting head removed; Fig. 7 is a detail showing an elevation of the supporting head removed from the machine; and Fig. 8 is a detail showing a section taken

upon the line 8—8 of Fig. 4 and looking in the direction of the arrow.

The machine shown in the illustrated embodiment of the invention is employed for setting rivets in various kinds of work and comprises essentially a rivet setting lever 2 fulcrumed upon the machine frame 3 at 4 and operated in the usual manner from the 55 driving shaft 5 through a crank and adjustable connecting rod 6. The rivet setting lever actuates a sliding plunger 7 and the rivets are positioned in alinement with the plunger by the usual type of positioning 60 head or tube 8 which is supplied automatically with rivets by a feeding chute indicated at 9. The feeding chute is connected with a hopper 10 supported upon the upper portion of the machine frame and provided 65 with agitating mechanism 11 operating from the setting lever. As the present construction is well known in the art and forms no part specifically of the present invention it 70 has been only briefly described herein.

The present invention consists in providing certain improvements in the mechanism for automatically feeding caps to the setting devices and is arranged to feed the caps 75 separately and at uniform intervals to position the cap in a predetermined location upon the setting anvil with relation to the setting plunger. It will be observed that each cap consists of a thin disk having an 80 annular inturned flange which forms what 85 may be conveniently referred to as the open face of the cap. In the illustrated embodiment of the invention the feeding mechanism positions each cap upon the setting anvil with the open face up and arranged to 90 receive the end of a rivet after it has been passed through the work. The caps are received in a rotary hopper indicated at 15 and supported upon a bracket 16 secured to the machine frame above the setting anvil in 95 order that the caps may be fed to the setting device by gravity. The hopper is conveniently rotated from the main drive shaft 20 through a drive belt 26, intermeshing worm gears indicated at 27 and a second drive belt 28 which engages with a belt receiving groove 30 formed in the shell of the hopper. The rotary hopper serves to deliver the caps 100 to the upper portion 41 of the feed chute in

an upright edgewise position and with the open faces all facing in the same direction.

As shown clearly in Fig. 1, the inclined portion 41 of the chute supplies caps to a vertical portion 45 in the lower end of which is provided mechanism for separating each cap and delivering it automatically and at the proper intervals to the setting mechanism. To this end a separator plate 50 is 5 slidingly supported in the lower end of the feed chute and is provided with separator fingers 51 and 52 projecting into opposite sides of the passageway and arranged to permit a single cap to be fed between them. The separator plate is normally retained in the position shown in Fig. 2 by a flat spring 53 secured to the side of the chute and having its free end bearing against the plate. This position of the plate causes the upper 10 finger 51 to project into the passageway and hold the line of caps. In order to automatically control the feed of caps to the setting anvil and insure that a single cap shall be positioned upon the anvil for the reception of each rivet, the separator plate is 15 operated in timed relation with the rivet setting lever. To this end the plate is moved to permit the feeding of one cap by a feed lever 55 pivoted to the frame 20 at 57 and having its lower end yieldingly connected with the plate through a spring 58, as shown clearly in Fig. 2. In the illustrated embodiment of the invention the movements imparted to the separator 25 plate by the feed lever are varied by pivoting the spring 58 to the lower end of the lever at 62 and providing an adjustable set screw 63 threadedly supported in the lower end of the lever and bearing against the member 58 to adjust the free end of the 30 member with relation to the lever. As stated previously, the feeding lever is actuated through the setting lever 2 and this is accomplished by providing the upper end 35 of the feeding lever with a curved cam surface 60 which engages with a roll 61 journaled upon the setting lever and so arranged that upon each oscillation of the setting lever to drive a rivet a feeding movement is 40 imparted to the separator plate 50 to permit a single cap to drop between the fingers. The separator plate is then returned immediately by the spring 53 and a single cap is 45 thus allowed to drop into an inclined chute 55 50 leading directly to a cap setting anvil 66. It will be noted that the caps are supported in the feed chute on their edges with their open faces facing in the same direction and in order to locate the caps in 60 the proper operative relation to the setting devices it is essential that they lie upon the setting anvil with the open face facing upward. This is conveniently accomplished in the illustrated embodiment of the invention 65 by providing the end of the inclined pas-

sageway with an inclined wall 68 which cooperates with an inwardly projecting plate 67, as shown clearly in Fig. 6, to form a deflecting passage for the cap. This portion of the passageway tips the cap into 70 an inclined position and communicates directly with a receiving bore 69 formed in a head 70 to feed the cap to the setting anvil in the position shown in Figs. 4 and 5. In order to secure the head 70 in place the end 75 of the chute is provided with oppositely disposed ears 71 which engage with the sides of the head and are secured thereto by set screws 75, as shown clearly in Fig. 3.

The caps are fed entirely by gravity in 80 passing from the supply hopper to the anvil. To permit a gravity feed, the caps are supported in an upright position so that they may roll on their edge. From the hopper 15 the caps are delivered to the supply section 41, from which they roll down to the vertical separating section 45. In the separating section the caps are released one at a time and roll down into the reciprocating feed section 65. The sections 41 and 45 85 have a comparatively steep inclination so that the caps will travel rapidly, but the inclination of the feed section 65 is made slight so that a cap, released from the separator 50, will roll slowly through the section 65, and will reach the deflector 68 with only sufficient momentum to turn over and land on the setting anvil without rebound.

It will be noted from an inspection of the drawings that with this type of machine 100 the work is normally positioned by the head 70 above the setting anvil and as the rivet is driven through the work the head is depressed from the position shown in Fig. 4 into that shown in Fig. 5. To this end the 105 head 70 is yieldingly supported in the position shown in Fig. 4 by a coiled spring 72 and the inclined chute 65 is rigidly connected with the head at one end and slidably connected at its opposite end with 110 the lower portion of the vertical chute 45. In order to form a continuous closed passageway for the caps at all times the inclined chute 65 is provided with a curved tongue 73 which projects within the lower 115 end of the vertical chute 45 and slides between the side walls of the chute, as shown clearly in Fig. 2. The upper side of the inclined chute is inclosed by a cover plate 76 detachably secured to the chute by set 120 screws 77 and having an upturned flange 74 which slidably contacts with the side of the feed chute 45 to form a completely closed passage for the caps. The inclined portion of the chute is guided in its vertical movements by a depending guide rod 79 which is 125 slidably received in a stationary guide member 80 secured to the machine frame, as shown clearly in Figs. 1 and 2.

While it is preferred to employ the spe- 130

cific construction and arrangement of parts shown and described, it will be understood that this construction and arrangement is not essential except so far as specified in the 5 claims, and may be changed or modified without departing from the broader features of the invention.

The invention having been described, what is claimed is:

- 10 1. A rivet and cap setting machine comprising a setting anvil, an inclined chute arranged to support caps on their edges and having a deflecting passage at the end of the chute to turn the caps to a flat position as 15 they reach the setting anvil, a cap separator, and mechanism for actuating the separator to release individual caps.
- 20 2. A rivet and cap setting machine comprising a setting anvil, a chute for supporting and guiding a series of caps including an inclined portion arranged to support the caps on their edges and having a deflecting passage to turn the caps toward their closed faces and deliver them to the setting anvil 25 with their open faces upward, a separator for releasing individual caps from the series in the chute, and mechanism for actuating the separator from the rivet setting mechanism.
- 30 3. A rivet and cap setting machine comprising a setting anvil and plunger, a plunger actuating lever, mechanism for automatically delivering rivets to the setting device, a chute for guiding caps on their edges 35 including an inclined portion arranged to deliver caps to the setting anvil, a gravity separator operated in timed relation to the plunger actuating lever for delivering individual caps from the series in the chute, and 40 a deflector for turning the caps to a flat position on the anvil.
4. A rivet and cap setting machine comprising a setting anvil for rigidly supporting the cap and a coöperating rivet setting plunger, a yielding head surrounding the anvil and provided with a cap receiving bore, and a feed chute for supporting and 45 guiding the caps provided with an inclined portion connected to move vertically with the head and having an exit end arranged to deliver the caps on to the setting anvil.
5. A rivet and cap setting machine comprising a vertical feed chute, a yielding work support, an inclined chute secured to 55 the work support and having a tongue projecting within the vertical chute, and an upturned flange engaging with the outside of the chute to form a continuous closed passage for the caps.
- 60 6. A rivet and cap setting machine comprising a work support having a cap receiving bore, an inclined feed chute for supporting

ing the caps on their edges provided with a passageway having an inclined wall, and an inwardly projecting plate secured to the 65 chute to form a deflecting passage communicating with the cap receiving bore in the work support.

7. A rivet and cap setting machine comprising a vertical feed chute, a yielding 70 work support, an inclined feed chute secured to the work support and slidingly connected with the vertical chute, a guide rod depending from the inclined chute, and a member slidingly receiving the rod to guide the vertical movements of the inclined chute.

8. A rivet and cap setting machine comprising a cap supporting anvil and coöperating rivet setting plunger, a yielding work supporting head surrounding the anvil and 80 provided with a cap receiving bore, a feed chute connected with the head for delivering caps to the bore, and means operated by the setting mechanism for delivering individual caps through the chute to the cap 85 receiving head.

9. A rivet and cap setting machine comprising a setting anvil and a coöperating rivet setting plunger, a plunger actuating lever, a reciprocatory head surrounding the 90 anvil, a cap feeding chute connected with said head, a cap supplying chute connected with the feed chute, and a yieldable connection between the feed chute and the supply chute to permit the feed chute to move 95 with the head during the rivet setting operation.

10. A rivet and cap setting machine comprising a setting anvil, a gravity feed chute through which caps roll on their edges to 100 the anvil, and a deflector connected with the chute, adjacent the setting anvil, to turn the caps to a flat position as they reach the anvil.

11. A rivet and cap setting machine comprising a setting anvil, and a gravity feed 105 chute having a slot through which caps roll on their edges to the anvil, said chute having a feeding section of slight inclination to deliver to the anvil without rebound.

12. A rivet and cap setting machine comprising a setting anvil, a gravity feed chute having a slot through which caps roll on their edges to the anvil, said chute having a supply section, a feeding section having a slight inclination to retard the rolling 110 movement of the caps, and a deflector near its end to turn the caps about their closed side and position them on the anvil in a flat position.
